UNITED STATES PATENT OFFICE.

HENRY W. STEINER, OF EASTON, PENNSYLVANIA, ASSIGNOR OF ONE-HALF
TO GUS W. ESCHENBACH, OF SAME PLACE.

SPOOL-HOLDER.

SPECIFICATION forming part of Letters Patent No. 408,328, dated August 6, 1889.

Application filed January 22, 1889. Serial No. 297,125. (No model.)

To all whom it may concern:

Be it known that I, HENRY W. STEINER, a citizen of the United States, residing at Easton, in the county of Northampton and State of 5 Pennsylvania, have invented new and useful Improvements in Spool-Holders, of which the following is a specification.

The invention relates to a spool-holder designed to hold the spool in knitting and sewing; and it consists in a certain novel construction and combination of devices, fully described hereinafter in connection with the accompanying drawings, and specifically pointed out in the claim.

15 In the drawings, Figure 1 is a perspective view of the improved holder with a spool applied in the operative position thereto. Fig. 2 is a similar view of the holder, with the spool removed.

20 Referring by letter to the drawings, A designates a safety-pin, of the ordinary or any preferred shape, except that it is provided on its stationary side with an eye B, and C designates a loop-shaped wire spring, which is 25 bent into an eye C' at its closed end, said eye being loosely engaged in the eye B. The arms c c of the said spring stand in the same transverse longitudinal place, and are corrugated oppositely, being provided with a series

30 of outwardly-extending bends D D, as shown clearly in the drawings. The width of the spring from the extremities of the bends on one side to the extremities of the bends on the other side is greater than the width of

35 the opening or bore of the spool E, and, therefore, to insert the spring in the spool the arms c c must be pressed together. When the spring is released, the outer ends of the corrugations or loops bear against the sides of 40 the bore of the spool and hold the latter in position.

The operation of the improved spool-holder will be evident. The pin is engaged in the dress or some portion of the wearing-apparel 45 of the operator, thereby preventing the spool from being mislaid and holding it within convenient reach of the operator, and different spools may be attached to the holder without removing the latter from its position as pinned 50 on the dress. When the thread is drawn from a spool, which is affixed to the improved

holder, the latter does not rotate, and therefore does not chafe the dress of the operator; but the thread simply uncoils or unwinds from the shank of the spool, its body sliding 55 over and around the lower enlarged end thereof. It is obvious that when the pin A is secured to the dress of the user the holder will normally depend and hang downward loosely therefrom; whereby the free end of 60 the spool is at the bottom. In this position the thread readily unwinds therefrom when the tatting, knitting, or other work is held near the lap of the user; but my improved device, by reason of its hinged connection 65 with the eye B of the pin, possesses the advantage over devices of this character now upon the market, in that when the work is raised by the user to a position near her eyes, as for close inspection or in case she be near- 70 sighted, the holder will turn on the eye, so that the free end of the spool will be uppermost. The thread will still unwind therefrom without difficulty and without necessitating the rotation of the spool, resulting in 75 a wear of the user's dress or involving a checking of the supply of thread, as would be the case if the pin and holder were integral or rigid.

The spool is held in place by the frictional 80 contact between the arms of the spring and the bore of the spool, and to remove the spool it is simply drawn out forcibly.

Having thus described the invention, I 85 claim—

The herein-described spool-holder, the same comprising the pin A, having an eye B in its lower stationary bar, and the loop-shaped wire spring C, bent into an eye at its upper end, loosely engaging said eye B in the pin, 90 side arms c c of said spring being oppositely corrugated and standing in the same plane, the whole adapted for use substantially as and for the purpose set forth.

In testimony that I claim the foregoing as 95 my own I have hereto affixed my signature in presence of two witnesses.

HENRY W. STEINER.
